UNITED STATES PATENT OFFICE.

JOHN L. BARRY, OF SCITUATE, MASSACHUSETTS.

PACKAGING YARN, THREAD, AND THE LIKE.

Application filed October 1, 1924. Serial No. 740,966.

My invention relates to the packaging of yarn, thread, and the like, which are commonly retailed in units of comparatively small quantity. The invention is particularly well suited to the packaging of embroidery yarns of silk, cotton or similar materials, and this application of the invention will be here taken for the purpose of illustration though it will be understood that the precise embodiments here shown and described are to be regarded as but illustrative of my invention and not by way of limiting the scope thereof. I have used the word yarn in this specification to include thread and other like materials.

At the present time embroidery yarn is commonly put up in skeins or hanks having, in one piece, eight or ten turns or loops, in which each turn or loop of the yarn is ordinarily a yard long or thereabouts, the hank being folded or doubled and encircled around its middle portion by a paper band so that the ordinary package for retail sales purposes is approximately six inches long and a fraction of an inch in diameter and contains about eight or ten yards. The preparation of such a package involves many hand operations, and though it answers fairly well the requirements of the retailer, it is to the consumer, extremely wasteful and troublesome to handle, use, and stow. To use the package it is first necessary to remove the paper band which holds the hank folded or doubled. Thus, at the outset, the label with its identifying name, trade-marks and symbols is separated from the package and perhaps lost or discarded, making it more difficult for the consumer to buy or duplicate the precise brand, variety and shade wanted. If the consumer, in an effort to minimize snarling, cuts through the hank and severs the loops of the hank so that they may be held end for end in a bunch as long as the length of the loop, and threads a needle as is commonly done with one full length equal to one loop (about a yard), any unused balance of the threading is inconvenient to save and hence frequently thrown away. Other methods have been devised for avoiding the whole or a part of the difficulties above described, but they do not have the advantages of the invention hereinafter described.

The objects of the present invention are to provide a package that is both economical and convenient to make and use, and which

permits the withdrawal of any desired length of the yarn without materially affecting the utility, shape or attractive appearance of the package until practically all of the yarn has been withdrawn. Thus wastage of yarn is eliminated, for only such yarn as is necessary need be severed from the package and the remainder is maintained in one unsnarled, wrapped package ready for immediate use. A further object of the invention is to provide a package which may be wrapped in a paper band or label and remain so wrapped while the package is being used, thus retaining the advertising and identifying value of the wrapper or band. In some cases no band or wrapper is desired, and it is one of the objects of this invention to provide such a package at no sacrifice of utility.

In the drawings illustrating the package and methods of making the same:

Fig. 1 is an elevation illustrating the step of winding the yarn upon a suitable spindle;

Fig. 2 is a perspective view illustrating the step of elongating the wound yarn in order to reduce the internal diameter of the coil;

Fig. 3 is an elevation illustrating a complete package made in accordance with this invention;

Fig. 4 is an enlarged end elevation of the same; and

Fig. 5 is an elevation of the package shown in Fig. 3 with the addition of a suitable encircling band.

Referring to the drawings:—

Fig. 1 shows the first step in making a package and illustrates the yarn upon a spindle of a winding machine which has completed the winding. This is done, preferably, by means of first winding the yarn or the like on a spindle by what is commonly known in the trade as the "universal" wind in which the yarn, thread, or cord is, as well known in the art and described by the manufacturer of the machines, "wound on a spindle in regular close helical coils which reverse with a sharp bend, each coil crossing over the next preceding coil, binding it in place at each crossing". Cops so wound are known to manufacturers as "close coils" or "close wound" if each turn is in contact with the preceding turn, or "evenly spaced open wind," if the turns are somewhat separated. I prefer the "close coils" but the evenly spaced "open wind" may be used if desired though

ordinarily less satisfactory. In this specification I have used the term "close wound" or "close coils", and "evenly spaced open wind" to mean packages so wound respectively and 5 I have used the term "universal wind" to include both types. 2 designates the spindle of the winding machine which is rotated as indicated by the arrow at a suitable speed; 4 the inner or starting end of the yarn 10 initially held fixed with reference to the spindle 2 by means of the spring clip 6 or other suitable means from which it can readily be released; 8 the coils of yarn upon the spindle; 10 the bends at the ends of the 15 coils; and 12 the outer end of the yarn which has been regularly led back and forth (by means not shown) traversing a given length of the spindle during its rotation so as to produce a suitable wind, and preferably 20 carry out the method described in United States Patent, No. 480,158, of Simon W. Wardwell, granted August 2, 1892, though I do not confine myself to such wind.

In the preferred wind here shown the 25 thread guide in its first traverse from above the inner to the outer end of the spindle forms three complete turns of the thread around the spindle and on the reverse traverse of the thread guide three more complete 30 turns are made around the spindle, each crossing the thread laid at the outward traverse at almost a right angle and so on throughout the winding operation, each thread being ordinarily laid close to the 35 thread laid by the first reciprocation by reason of the "gainage" given to the thread guide. It will be observed that the effect of this is that when the cop is removed from the spindle the threads are in effect 40 woven together and each thread is held in place against collapse and tangling by a wall of interior thread with the exception of the few inches constituting the yarn wound at the first traverse of the thread 45 guide to the end of the spindle and that length is held separate from the other threads by crossing them almost at right angles. The cop when withdrawn from the winding spindle is approximately a hollow 50 cylinder. My next step is to remove permanently this hollow portion by elongating the cop.

Fig. 2 illustrates the step (here but partially completed) of elongating after the winding has been performed, the coiled product of the winding machine being seized at its opposite ends and stretched longitudinally. This is here shown as being done by hand after the removal of the coiled product 55 from the spindle which may be and preferably is slightly tapered to facilitate the removal, that is, the spindle may be of smaller diameter at the end, and tapered towards the end, from which the yarn is removed. 60 It is then elongated or stretched longitudi-

nally until a substantial amount, and preferably substantially all, of the space formerly occupied by the spindle is absorbed by the reduction of the internal diameter or central void, the external diameter being 70 correspondingly reduced. I have discovered that this attenuation imparts a stability and compactness to the package which enables it to withstand the subsequent withdrawal of the thread by its inner end 4 without adverse 75 results. The reduction of the internal central void results in an increase in length, as for example, if about nine yards of embroidery yarn is wound upon a $5\frac{1}{4}$ " spindle so that there are three complete turns 80 in three inches of the spindles' length before reversal or bend of the yarn at the ends, and the wound product is stretched until its internal diameter is reduced to a minimum it will be found that the resulting 85 package is approximately twice as long. The angle at which the threads cross is slightly changed but the coils remain mutually supported and the cop, if originally close wound remains close wound. The effect 90 of this extension is to produce a package such as would be formed if it were possible, which it is not, to wind the cop upon a spindle of infinitesimal diameter and yet obtain a cop having a length corresponding 95 to the traverse of the thread guide and otherwise regularly laid as designed. It is, of course, contemplated that this step may be performed by machine as well as by hand.

Figs. 3 and 5 represent illustrative embodiments of this invention. The packages here shown are ready for packing, shipment or use, and either may be used by simply withdrawing any desired length of the yarn from the inner end of the package. Ordinarily an encircling paper band 14 bearing the name and trade-mark, together with identifying and descriptive matter, will be preferred by both dealer and user, but in case it is dispensed with, it is simply necessary to tuck the outer or free end 12 of the yarn under one of the outer coils or turns (as indicated at "w" in Fig. 3) so that the outer end of the yarn package does not unwind during handling. The outer end 12 should preferably be beneath the wrapper, if a wrapper is used (as in Fig. 5) in order that it may hold the outer end of the yarn from unwinding. The inner end 4—the end from which the yarn is withdrawn, takes care of itself.

Fig. 4 is an end view of the package shown in Fig. 3 and illustrating the end of the package from which the yarn is withdrawn by its inner end 4. The use of the foregoing method results in a new and useful package.

A wind means the yarn wound at each complete revolution of the spindle, and a

package is spoken of, for example, as "3 wind" if the coils making up the package are 3 wind coils, that is, if in winding it, the spindle has made approximately three rotations

5 or complete turns or revolutions in winding a coil, that is, for each one way traverse of the guide which leads the yarn being wound back and forth from end to end of the package, or as "3½ wind", if the 10 spindle has made approximately 3½ rotations per traverse of the guide from one end of the package to the other.

Having described my invention, what I 15 wish to claim and secure by Letters Patent is:—

1. A yarn package adapted for domestic use comprising in combination, an elongated flexible approximately cylindrical body having no appreciable central void and not being materially extensible longitudinally, 20 formed of yarn wound in helical coils which reverse with abrupt bends at the ends of said body, each coil having more than one wind and crossing the next preceding coil 25 intermediate the ends of said body and binding said coil in place at each crossing, the inner end of the yarn strand being available and withdrawable from said body, and means for confining the outer end of said 30 strand.

2. A yarn package adapted for domestic use comprising in combination, an elongated flexible approximately cylindrical body having no appreciable central void and not being materially extensible longitudinally, 35 formed of yarn wound in helical coils which reverse with abrupt bends at the ends of said body, each coil having between one and six winds and crossing the next preceding 40 coil intermediate the ends of said body and binding said coil in place at each crossing, the inner end of the yarn strand being available and withdrawable from said body; and a suitable band surrounding said body intermediate the ends thereof.

3. A yarn package adapted for domestic use comprising in combination, a flexible approximately cylindrical body having a length of at least 4 times its diameter, with 50 no appreciable central void and not being

materially extensible longitudinally, formed of yarn wound in helical coils which reverse with abrupt bends at the ends of said body, each coil having approximately three winds and crossing the next preceding coil intermediate the ends of said body approximately 55 five times and binding said coil in place at each crossing, the inner end of the yarn strand being available and withdrawable from said body; and a band of suitable material surrounding said body intermediate the ends thereof and confining the outer end of the yarn strand.

4. The method of producing an elongated approximately cylindrical yarn package 60 adapted for domestic use which consists in winding on a spindle a yarn body consisting of helical coils of more than one wind and which reverse with abrupt bends at the ends of said body, each coil crossing the next 65 preceding coil intermediate the ends of said body and binding said coil in place at each crossing; then removing said body from the spindle; then stretching said body longitudinally to close the central void left by the withdrawal from said spindle; then confining the outer end of the yarn strand; and at some stage of the process rendering and thereafter maintaining the inner end of the 70 yarn strand withdrawable from said body. 80

5. The method of producing an elongated approximately cylindrical yarn package 85 adapted for domestic use which consists in winding on a spindle a yarn body consisting of helical coils of more than one wind and which reverse with abrupt bends at the ends of said body, each coil crossing the next preceding coil intermediate the ends of said body and binding said coil in place at each crossing; then removing said body from the spindle; then stretching said body longitudinally to close the central void left by the withdrawal from said spindle; then banding said body in such a manner as to confine the outer end of yarn strand; and at some stage 90 of the process rendering available and thereafter maintaining the inner end of the yarn strand withdrawable from said body. 95
